CLAIM

The ornamental design for a container for cleansing wipes, as shown and described.

DESCRIPTION

FIG. 1 is a perspective view of our new design with the lid open;

FIG. 2 is a top elevational view thereof with the lid open;

FIG. 3 is a rear elevational view thereof with the lid closed;

FIG. 4 is a front elevational view thereof with the lid closed;

FIG. 5 is a bottom elevational view thereof with the lid open;

FIG. 6 is a right side elevational view thereof with the lid open;

FIG. 7 is a left side elevational view thereof with the lid open; and,

FIG. 8 is a perspective view thereof with both the lid and a surface closure open.

The broken lines in the drawings depict environmental subject matter only and form no part of the claimed design.
